UNITED STATES PATENT OFFICE.

THOMAS F. HART, OF LYNN, MASSACHUSETTS, ASSIGNOR TO MICHAEL L. HILLER, OF NEW YORK, N. Y.

BUTTON-HOLE SEWING-MACHINE.

SPECIFICATION forming part of Letters Patent No. 363,823, dated May 31, 1887.

Application filed June 16, 1886. Serial No. 205,334. (No model.)

To all whom it may concern:

Be it known that I, THOMAS F. HART, a citizen of the United States, residing at Lynn, in the county of Essex and State of Massachusetts, have invented certain new and useful Improvements in Button-Hole Sewing-Machines for Sewing Round Holes; and I do hereby declare that the same are fully described in the following specification and illustrated in the accompanying drawings.

This invention relates to improvements in button-hole sewing-machines for the purpose of stitching around the edges of round holes; and it is carried out as follows, reference being had to the accompanying drawings, where—

Figure 1 represents a front elevation of an ordinary button-hole sewing-machine provided with my improvement. Fig. 2 represents a plan view of the clamp. Fig. 3 represents a sectional side elevation of the clamp with the button-plate, bed, and clamp-operating gear shown in section. Fig. 4 represents a perspective detail view of the driving and clamp-operating gears. Fig. 5 represents a plan view of the button and button-plate. Fig. 6 represents a detail perspective view of the clamp guide-block, and Fig. 7 represents a plan view of a piece of work done on the machine.

Similar letters refer to similar parts wherever they occur on the different parts of the drawings.

a is the bed, *b* the goose-neck, and *c* the vertically and laterally movable needle-bar, as usual on button-hole sewing-machines.

c' is the needle secured to the lower end of the needle-bar *c*, as shown in Fig. 1.

In a recess, *a'*, in the top of the bed *a* is located the usual driving-gear, *d*, attached to shaft *d'*, that is set in a rotary motion from the driving-shaft of the sewing-machine in the usual manner. The gear *d* meshes into the teeth of the clamp-operating gear *e*, that is made to turn around the annular ring *a''*, forming a part of the bed *a*, as shown in Figs. 3 and 4.

a'' is a central perforation in the interior of the annular ring *a''* for the needle to pass up and down through in forming the stitches. On the upper side of the clamp-operating gear *e* are a number of radial ribs or walls, *e' e''*, and intermediate recesses or grooves, *e'' e'''*, as shown

in Figs. 3 and 4, for a purpose as will herein-after be more fully described.

f is the button-plate secured to the top of the stationary annular ring *a''* by means of suitable screws *f' f' f'*, as shown in Figs. 3 and 5, and to the central portion of such button-plate is secured the button *f''*.

f'' is a vertical slotted perforation through the button *f* for the vertically and laterally movable needle *c* to pass when forming the stitches. Above the button-plate *f* is located the clamp-plate *g*, having a central grooved perforation, *g'*, into which the button *f''* projects, such perforation being, however, larger in diameter than the button *f''*, according to the size of the hole *H'* in the material, *H*, (shown in Fig. 7,) to be button-hole stitched.

Secured to and rising from the clamp-plate *g* is the hollow clamp-post *h*, in which is vertically adjustable the stud *h'*, having knob or handle *h''* on its upper end and normally held in the operative position shown in Fig. 3 by the influence of the coiled spring *h''*. The lower end of the stud *h'* is made to project in any desired one of the grooves or recesses *e''* on the upper portion of the clamp-operating gear *e*, as shown in Fig. 3. To the front of the post *h* is secured, or made in one piece with it, the ear *h'*, to which is pivoted at *h''* the *T* *i*, to the front of which are secured the clamp-arms *I I*. (Shown in Figs. 2 and 3.)

k represents the annular clamp-jaw, having upwardly-projecting pins *k' k'* projecting through perforations in the free ends of the clamp-arms *I I* and pivoted to the latter in a suitable manner, as shown in Figs. 2 and 3.

l l are pressure-springs located between the upper side of clamp-plate *g* and under side of the clamp-arms *I I*, as shown in Fig. 3, for the purpose of automatically raising the clamp-arms *I I* to the position shown in Fig. 3 as soon as the pressure device is relieved.

The material to be stitched is confined and held firmly between the under side of the annular clamping-jaw *k* and central upper portion of the clamp-plate *g* by means of the pressure device shown in Figs. 2 and 3, such pressure device consisting of the vertical rod *m*, rising from and secured to the clamp-plate *g*, and provided with a horizontal pin or projection, *m'*, at or near its upper end. Surround-

ing the rod m is a sleeve, n , having attached to its upper end a crank, n' , and having a cut-away cam-surface, n'' , as shown in Fig. 3.

- n^3 n^3 are ears on the under side of the sleeve 5 n , bearing on the uppersides of the clamp-arms II, as shown in Figs. 2 and 3. After the material to be stitched is placed between the central portion of clamp-plate g and under side of clamp-jaw k the latter is forced downward 10 upon the upper side of the material, so as to hold it firmly in place on the clamp-plate by turning the sleeve n a part of a revolution around the rod m , causing it to move downward by the cam-surface n'' acting on the stationary projection m' on rod n , by which operation the ears n^3 n^3 are caused to force the free ends of the clamp-arms II downward, and with them the clamp-jaw k . After the edge of the circular hole in the material H has 15 been button-hole stitched said material is released from its confinement between the clamp-plate g and clamp-jaw k simply by turning the crank n' and its sleeve n in an opposite direction around the stationary rod m , allowing the clamp-arms II to rise by the influence of the springs ll .

- During the operation of button-hole stitching the edge of the hole H' in the material, H , the clamp-plate g , and the clamp-jaw k are 20 made to partake of the rotation of the clamp-operating gear e by the lower end of the stud h' resting in any one of the grooves or recesses e'' e'' on the said gear e ; and the object of such recesses or grooves e'' e'' is to enable the stud h' to be placed in front of the operator and 25 locked to the gear e when commencing the work on a new piece of material, and thus to facilitate the proper placing of the material on the clamp-plate before the machine is set in 30 operation. In button-hole stitching a circular hole it has been found necessary to rotate the clamp-plate a little more than one complete revolution, and if it were not for the grooves or recesses e'' e'' on the clamp-operating gear e , combined with the vertically-adjustable stud h' , the position of the clamp would vary after the 35 completion of each piece stitched, and this objection is entirely overcome by the aforesaid clamp-adjusting device.
- For the purpose of properly guiding the clamp-plate g during its eccentric rotation around the button f'' , I secure, in an adjustable manner, to the under side of the button-plate f the clamp-guide block o , (shown in Fig. 3, as well as in detail in Fig. 6,) such guide-block having an upwardly-projecting lip, o' , 40 that is held against the interior edge of the perforation g' in clamp-plate g , and said guide-block is capable of a lateral adjustment by means of the set-screw o'' , passing through a slot-hole, o^3 , in the guide-block o and screwed into a screw-threaded perforation in the button-plate f , as shown in Fig. 3.
- The perforation g' in clamp-plate g , in proportion to the diameter of button f'' , is made 45 according to the diameter of the hole H' to be button-hole stitched in the material, H .
- f^4 is a slot-hole in the button-plate f , through which the lip o' projects, to enable the guide-block o to be adjusted laterally for the purpose set forth.

The operation of forming the stitches is the same as in ordinary button-hole sewing-machines, and need not here be described.

What I wish to secure by Letters Patent 75 and claim is—

1. In a button-hole sewing-machine for the purpose set forth, the rotary clamp-operating gear e and its notches or recesses e'' e'' , combined with the clamp-plate g and yielding 80 clamp-jaw k , connected to the clamp-arms II, means, substantially as described, for forcing the arms II downward, and the vertically-adjustable spring-pressed pin h' , for locking the clamp-plate g and notched gear e together in 85 any desired position, as set forth.

2. In a button-hole sewing-machine for the purpose set forth, the stationary button-plate f and its perforated button f'' , in combination with the horizontally-adjustable clamp guide-block o and its upwardly-projecting lip o' , adapted to bear against the interior edge of the perforation g' in clamp-plate g , the clamp-jaw k and its arms II, the clamping device, as described, and means, substantially as described, 95 for locking the gear e and clamp-plate g together, as set forth.

3. In a button-hole sewing-machine for the purpose set forth, the stationary plate f and its perforated button f'' , the rotary gear e , having notches or recesses, as described, the plate g , having the spring-pressed pin h' , for connecting it to gear e , the clamp-plate k , mounted on or connected to clamp-arms II and having springs ll , and clamping device, all arranged 100 and combined substantially as and for the purpose set forth.

In testimony whereof I have affixed my signature in presence of two witnesses.

THOMAS F. HART.
